US0D1099309S

(12) **United States Design Patent** (10) Patent No.: **US D1,099,309 S**
(45) Date of Patent: ** Oct. 21, 2025

(54) **BRACKET FOR RESPIRATORY SENSING DEVICE**

(71) Applicant: **3M INNOVATIVE PROPERTIES COMPANY**, St. Paul, MN (US)

(72) Inventors: **Jacob P. Vanderheyden**, St. Paul, MN (US); **John M. Pilgrim**, Woodbury, MN (US); **David M. Castiglione**, Hudson, WI (US); **Graham Peter Wilson**, Flint (GB); **Simon Matthew Pougher**, Parkgate (GB); **Samuel Wyn Jones**, Ewloe (GB)

(73) Assignee: **3M Innovative Properties Company**, St. Paul, MN (US)

(**) Term: **15 Years**

(21) Appl. No.: **29/940,673**

(22) Filed: **May 3, 2024**

CLAIM

The ornamental design for a bracket for respiratory sensing device as shown and described.

DESCRIPTION

FIG. 1 is a perspective view showing another embodiment of the new design for a bracket for respiratory sensing device;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines show portions of the bracket for respiratory sensing device that form no part of the claimed design

1 Claim, 6 Drawing Sheets
